Primary Examiner — Nathan M Johnston(74) *Attorney, Agent, or Firm* — Fitch, Even, Tabin & Flannery LLP(57) **CLAIM**

The ornamental design for a modular wall mount for a vehicle, as shown and described.

DESCRIPTION

FIG. 1 is a front perspective view of a modular wall mount for a vehicle in accordance with a first embodiment of my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left elevation view thereof;

FIG. 7 is a right elevation view thereof; and,

FIG. 8 is an enlarged view of the circled portion “8” in FIG. 1.

My design includes a second embodiment of a modular wall mount for a vehicle that is a mirror image of the design shown in FIGS. 1-8.

The dash-dot lines forming a circle in FIGS. 1-8 form no part of the claimed design. The broken lines depict portions of the mount that form no part of the claimed design.
